FILLING APPARATUS AND METHOD

William McK. Martin, San Mateo, and Alexis E. Post, San Francisco, Calif., assignors to James Dole Engineering Co., a corporation of Nevada

Application December 27, 1949, Serial No. 135,116

4 Claims. (Cl. 226—95)

1

This invention relates to the continuous filling of a product in containers, and more particularly to an improved apparatus and method for the filling of containers which are not placed side by side with their mouths in contacting relationship to thus enable the containers to be filled without spillage as they are moved past a continuous stream of the product.

In copending application, Serial No. 104,074, filed July 11, 1949, for "Apparatus and Method for Filling Products in Containers," is disclosed a special type of continuous filler which feeds a continuous stream of any suitable liquid product into containers which are continuously conveyed in a line, which may be arcuate but is preferably straight, along or past the filler at such speed as to cause each container to be substantially completely filled as it passes by the filler. The containers are conveyed with a substantially continuous or uninterrupted motion, so that spillage of the contents is obviated which would otherwise result if the containers were held stationary under the filler during the filling operation, and consequently have to be moved after each filling operation, with the result that the entire line of containers would have to be moved with an interrupted motion.

Such type of filler is particularly adapted for the filling of can containers which have the usual flanges at their open mouths because the product can be introduced into the containers without spillage when the containers are moved past the filler with their flanges overlapped. Although such filler can fill containers positioned with their mouths spaced apart, this is undesirable because of the spillage of the product which would obtain by virtue of the spaces between the mouths of the containers.

Summarizing this invention, it embodies the principle disclosed in the aforementioned application wherein the containers are conveyed in one general direction past a continuous stream of the product with a continuous substantially uninterrupted motion. However, the filler is designed to enable filling, with substantially no spillage, of containers the mouths of which cannot be positioned in adjacent contacting relationship; for example, a glass jar container in which the mouth is of lesser diameter than the body of the container, as well as various other types of containers having such arrangement.

The filler of this invention is elongated and has an elongated discharge opening adapted to span the mouths of a plurality of containers which are continuously moved past the filler by suitable

2

conveying means, with an uninterrupted motion and in predetermined relationship. A rotatable valve member is provided in the filler, and has a helical peripheral control passage which upon rotation of the valve member supplies a continuous stream of the product through the discharge opening, which stream is divided into a plurality of spaced apart branches. By virtue of the helical control passage of the valve member the stream branches are caused to move continuously in the general direction in which the containers are conveyed past the filler. The spacing of the containers as they move past the filler is such that each container is positioned underneath a branch of the stream, so that each container becomes completely filled in its travel past the filler.

Referring to the drawings:

Fig. 1 is a more or less schematic longitudinal sectional elevation of the filler apparatus, with parts shown broken away to illustrate more clearly the invention;

Fig. 2 is a fragmentary plan view of Fig. 1; the filler unit being omitted from the view for purposes of clarity;

Fig. 3 is an end elevation of Fig. 1 looking in the direction of arrow 3 in Fig. 1;

Fig. 4 is a transverse vertical section taken in a plane indicated by line 4—4 in Fig. 1;

Fig. 5 is a schematic view of the apparatus illustrating the manner of feeding the product thereto;

Fig. 6 is an enlarged longitudinal vertical sectional view through the filler unit, illustrating details of construction;

Fig. 7 is an end elevation looking in the direction of arrow 7 in Fig. 6;

Fig. 8 is a fragmentary longitudinal vertical section at an end of the filler unit, illustrating means for providing a sterile seal when the filler is employed in the aseptic filling of products in the manner disclosed in the aforementioned application;

Fig. 9 is a transverse vertical sectional view of the filler adapted for use under the described aseptic sealing conditions.

With particular reference to Figs. 1, 4 and 6, the filler unit comprises a substantially cylindrical filler casing 2 which is formed of a tubular body part 3 and a discharge opening plate part 4 detachably connected to body 3 by cap screws 5. Plate 4 is provided with a straight elongated discharge opening 6 extending from adjacent one end of the filler unit to the other; and a drip shield 6' is secured under plate 4

by the cap screws 5. A cylindrical valve member 7 is removably mounted and journalled for rotation in casing 2, and is provided with a helical passage 8 in its peripheral wall; the passage 8 being for all practical purposes continuous, except for relatively short wall portions 9 spaced at relatively long intervals along the length of passage 8 to provide connecting means maintaining the valve member a structurally rigid unit. Casing 2 and valve member 7, as well as other parts of the filler unit, are formed of any suitable metal, preferably stainless steel, which can be readily cleaned and is relatively non-corrodible; and the outer surface of the wall of valve member 7 has a relatively close sealed fit in casing 2.

Means is provided for sealing the ends of casing 2 and for mounting valve member 7 for rotation in the casing. Adjacent each end, casing 2 is fixedly secured to a mounting plate 11 which provides supporting means for the filler unit. At one end of the casing, namely, the end from which valve member 7 is rotatably driven, casing 2 is formed with a tapered seating surface 12 adapted to seat a removably mounted end sealing plug 13 having a complementary tapered seating surface adapted to seal against seating surface 12. Plug 13 is detachably clamped in the end of the casing by means of a cross bar 14 clamped against the end of the plug by cap screws 16 threaded in the mounting plate 11 adjacent such drive end of the casing.

A detachable driving connection is provided by shaft 17 which extends through apertures in the end of sealing plug 13 and in cross bar 14, and which is journalled in a suitable sealing and self-lubricating bearing 18, preferably of graphite, mounted in a recess in plug 13. The inner end of shaft 17 carries a collar 19 fitting the inside diameter of valve member 7 and which is provided with a detachable keyed driving connection 20 with the valve member; and the outer end of shaft 17 carries a sprocket 21 through which the shaft can be driven by a suitable chain driving connection.

At the end opposite the driving end, casing 2 is sealed by means of a second detachably mounted sealing plug 22 seated in such end of the casing in the same manner as sealing plug 13. However, plug 22 is closed at its outer end, and is provided with an inlet pipe connection 23 for feeding of the product to be filled into the filler; the inside of plug 22 being provided with a recess 24 to receive the product and allow it to flow into the interior of valve member 7. Plug 22 is removably clamped against the end of casing 2 by clamping bar 26 and screws 27 threaded in the mounting plate 11 adjacent the feed end of the filler.

Both ends of valve member 7 are formed with reduced diameter shoulder portions which seat bearing rings 28, each of which abuts the end of the adjacent end plug, and which are formed of the same material as bearing 18. From the preceding, it is seen that the described parts of the filler unit are all detachably connected, so that they can be quickly and easily taken apart for replacement or repair, and for cleaning of the filler when necessary.

Product is supplied to the filler from product supply tank 31 (Fig. 5) connected by piping 32 to inlet pipe 23 of the filler. Connected in piping 32 is a so-called constant volumetric discharge pump 33 which provides means for supplying a fixed predetermined quantity or volume of the product per unit of time; this quantity being reg-

ulatable at will by means of variable speed motor 34 connected to drive the pump.

In operation, it will be noted that the filler unit is stationary at a fixed zone or location. Liquid cannot flow out of the filler unit except at the spaced points where the helical control passage 8 crosses the elongated discharge opening 6 which, as can be seen from Fig. 1, spans the mouths of a plurality of containers 36 which are continuously conducted past the filler with a substantially uninterrupted motion in one general direction by means to be described. The stream of the product which flows out of the filler through discharge opening 6 is divided into a plurality of equally spaced apart branches 37, determined by the position of the points of crossing of helical control passage 8 over discharge opening 6.

Valve member 7 is continuously rotated at a predetermined fixed speed; and because of the helical character of passage 8 which is preferably of a constant lead or pitch, the points of such crossing of passage 8 over discharge opening 6 will continually change with the result that the branches 37 of the stream will continuously travel in equally spaced relationship from adjacent one end of the filler to adjacent the opposite end thereof; the direction of rotation of valve member 7 being such that such stream branches will travel in the same general direction as the containers are being moved.

In this connection, each branch 37 of the stream is initially formed at each revolution of valve member 7 when the end of the helical control passage 8 adjacent the drive end of the filler crosses discharge opening 6, and such branch will then be caused to travel the entire length of the discharge opening 6 as the valve member rotates, until it reaches a position adjacent the opposite end of the filler where the flow is shut off. Thus, a new stream branch is formed adjacent one end of the filler for each revolution of the valve member, and the successively formed stream branches will travel the length of discharge opening 6 in the described equally spaced apart relationship.

It is immaterial whether stream branches 37 travel from the drive end of the filler to the feed end thereof, or vice versa, as it is only necessary that they travel from adjacent one end of the filler to adjacent the opposite end, and that containers 36 be moved in the same general direction. Although valve member 7 is preferably in the form of a hollow cylinder with helical passage 8 formed in the wall thereof, it can be in the form of a conventional screw having an upstanding screw member formed on a shaft portion, in which the helical space between the screw flights forms the helical control passage. However, the construction illustrated is desirable because it provides for more efficacious feeding of the product and valving control thereof through discharge opening 6.

Any suitable mechanism may be provided for continuously moving containers 36 in the same general direction as the direction of travel of stream branches 37, and for positioning the containers in predetermined relationship with each container underneath a branch of the stream to effect filling of each container in its travel past the filler. In the embodiment of the invention illustrated, such mechanism comprises an endless conveyor 41 which moves the containers 36 in the direction of travel of stream branches 37 and which cooperates with means, in the form of

a worm structure 42, for positioning the containers in predetermined relationship on the conveyor with each container underneath a branch of the stream to effect filling of each container. As can be seen best from Fig. 2, worm 42 is positioned above conveyor 41 at one side thereof, and comprises a shaft member 43 journaled in bearings 44, and having a worm or helix 45 about the periphery thereof.

Worm 46 does not move the containers 36 but merely spaces them apart in the desired predetermined relationship; the pitch or lead of worm 46 being substantially the same as the pitch or lead of the helical valve control passageway 8 of valve member 7. Conveyor 41 is moved at a slightly faster speed than the speed of rotation of worm 46; and as a result, containers 36 will be always held against the worm which will maintain the proper spaced relationship between the containers so that they will be filled properly. If desired, the containers may travel on a stationary support, and worm 46 may be utilized to perform the double function of moving the containers and properly positioning them.

Guide means is provided at the side of conveyor 41 opposite worm 46, to maintain the containers in contact with the worm. At the end of the filler where the containers 36 first meet the same, such guide means comprises a stationary belt 47 which is spring pressed against the sides of the containers by rollers 48 mounted on pivoted arms 49 and thrust toward belt 47 by resilient means 51. The purpose of this arrangement is to provide a yieldable guide at the described location because the containers upon striking the end of worm 46 at such location may be deflected laterally, and might otherwise be broken, bent or jammed without the provision of such yielding means.

After the containers become properly positioned in the spaces between the flights of worm 46, such resilient guide means need not be employed, and the rest of the guide comprises a stationary side bar 52. With reference to Fig. 1, it will be noted that spacing worm 46 extends beyond the end of the filler which first meets the containers, so that the containers are in proper alignment and properly spaced apart by the time they are ready to be filled.

Any suitable means may be provided for driving the control valve member 7 and the worm 46 in timed relationship. In the embodiment of the invention illustrated, the drive is taken off a main drive shaft 56 which carries a sprocket 57. Sprocket 57 is connected by chain 58 to a sprocket 59 mounted on a countershaft 61 which is journaled in suitable bearing supports 62. Countershaft 61 also carries a sprocket 63 mounted for angular adjustment, by any suitable means 64, on a collar 66 secured to countershaft 61. A chain 67 connects sprocket 63 to a sprocket 68 secured for rotation with worm 46. Countershaft 61 has also secured thereto a third sprocket 69 which is connected by a chain 71 to the previously mentioned sprocket 21 which is secured for rotation with valve member 7 in the manner previously related. By the described arrangement, both worm 46 and valve member 7 can be simultaneously driven; and in this connection, adjusting means 64 for permitting angular adjustment of sprocket 63 enables an initial setting so that helical passage 8 in valve member 7 can be timed properly (i. e. have the same angular relationship) with worm 46.

The direction of rotation of the parts for feed-

ing the stream branches 37 and turning worm 46 in the proper direction with respect to the general direction of movement of containers 36 by conveyor 41, is shown by the direction arrows 5 D in the drawings. Since the constant volumetric discharge pump 33 feeds a constant volume of the product to be filled per unit of time as adjusted by variable speed motor 34, such quantity can be readily set relative to the speed of travel of the containers past the filler, so that each container can be substantially filled in its travel past the filler. At the same time, since each container is positioned underneath one of the stream branches 37 as it moves from adjacent one end of the filler to adjacent the other end of the filler, no spillage can occur even though the containers are spaced apart or their mouths are such that they cannot be positioned in side by side contiguous relationship with their bodies in contact.

The described apparatus is adapted for the continuous filling of any liquid product. Should it be employed in the aseptic sealing apparatus disclosed in the aforementioned copending application, it can be mounted in an insulated cover 76, as shown in Fig. 9, which is positioned over a filler housing 97 containing perforated piping 78 for maintaining a sterile atmosphere of superheated steam or any other sterile fluid in housing 77, in accordance with the principles disclosed in said aforementioned application.

With such employment of the filler, a sterile seal for the removable end plugs 13 and 22 may be provided by forming a peripheral groove 81 in each end plug, and introducing saturated steam in such groove by means of inlet piping 82, as is illustrated in Fig. 8.

We claim:

1. Apparatus for filling a product in containers comprising an elongated filler having an elongated discharge opening adapted to span the mouths of a plurality of such containers, means for supplying a substantially continuous stream of the product through said discharge opening divided into a plurality of spaced apart branches and moving said branches in one general direction, means for continuously conveying said containers past said filler in said direction, means for positioning said containers in predetermined relationship with each container underneath a branch of the stream to effect filling of each container in its travel past the filler, and means for supplying a predetermined fixed quantity of product to said filler per unit of time.

2. Apparatus for filling a product in containers comprising an elongated substantially cylindrical filler casing having an elongated discharge opening, removably mounted sealing plugs seated in the ends of said casing, a cylindrical valve member in said casing mounted for rotation therein, said valve member having a helical substantially continuous passage in its wall interrupted by relatively short wall portions and which upon rotation of said valve member supplies a substantially continuous stream of the product through said discharge opening divided into a plurality of spaced apart branches moving in one general direction, and means for rotating said valve member including a shaft extending through one of said end plugs and having a detachable driving connection with said cylindrical valve member.

3. Apparatus for filling a product in containers comprising a tubular filler casing having an elongated discharge opening, removably mounted

sealing plugs seated in the ends of the casing, a rotatable valve member in said casing having a helical passage interrupted by relatively short wall portions which upon rotation of said valve member supplies a substantially continuous stream of the product through said discharge opening divided into a plurality of spaced apart branches moving in one general direction, means for rotating said valve member including a shaft extending through one of said end plugs and having a detachable driving connection inside said casing with said valve member, said one end plug having an interior recess, a self lubricating bearing for said shaft housed in said recess, and a product inlet for said filler in the other of said end plugs.

4. Apparatus for filling a product in containers comprising a tubular filler casing having an elongated discharge opening, removably mounted sealing plugs seated in the ends of the casing, a rotatable valve member in said casing having a helical passage interrupted by relatively short wall portions which upon rotation of said valve member supplies a substantially continuous stream of the product through said discharge opening divided into a plurality of spaced apart branches moving in one general direction, means

10

25

for rotating said valve member including a shaft extending through one of said end plugs and having a detachable driving connection inside said casing with said valve member, said one end plug having an interior recess, a self lubricating bearing for said shaft housed in said recess, and a product inlet for said filler in the other of said end plugs.
